UNITED STATES PATENT OFFICE.

HYMAN WANERMAN, OF NEW YORK, N. Y.

DESIGN FOR A LIQUID REFRESHMENT DISPENSER.

Application filed January 11, 1927. Serial No. 20,334. Term of patent 3½ years.

To all whom it may concern:

Be it known that HYMAN WANERMAN, a citizen of the United States, and resident of the borough of Bronx, in the county of Bronx and State of New York, has invented a new, original, and ornamental Design for a Liquid Refreshment Dispenser, of which the following is a specification, reference being had to the accompanying drawing, forming part thereof, in which,

Fig. 1 is a top plan view of a liquid refreshment dispenser showing my new design.

Figs. 2 and 3 are side elevational and rear elevational views, respectively, thereof.

I claim:

The ornamental design for a liquid refreshment dispenser, as shown.

Dated New York, N. Y., January 7th, 1927.

HYMAN WANERMAN.
